COMBINED OSCILLOGRAPH RECORD DEVELOPER AND SCANNING TABLE OR THE LIKE

Reginald E. Greene, Chamblee, Ga., assignor to Lockheed Aircraft Corporation, Burbank, Calif.

Filed Feb. 25, 1963, Ser. No. 73,690

Term of patent 14 years

(Cl. D26—5)

FIG. 1.

FIG. 2.

FIG. 3.

FIG. 4.

FIGURE 1 is a perspective view of a combined oscillograph record developer and scanning table or the like showing my design;

FIGURE 2 is a front elevational view thereof;

FIGURE 3 is a rear elevational view thereof; and

FIGURE 4 is a side elevational view thereof as viewed from the right side of FIGURE 2.

The essential features of the design reside in the portions shown in full lines on the drawing.

I claim:

The ornamental design for a combined oscillograph record developer and scanning table or the like, substantially as shown and described.
